Patented May 19, 1925.

UNITED STATES PATENT OFFICE.

JOSEPH L. CUSHING, OF LOWELL, MASSACHUSETTS.

PNEUMATIC-CONVEYER SWITCH.

Application filed June 21, 1924. Serial No. 721,474.

To all whom it may concern:

Be it known that I, JOSEPH L. CUSHING, a citizen of the United States, residing at Lowell, in the county of Middlesex and 5 State of Massachusetts, have invented certain new and useful Improvements in Pneumatic-Conveyer Switches; and I do hereby declare the following to be a full, clear, and exact description of the invention, such as 10 will enable others skilled in the art to which it appertains to make and use the same.

The present invention relates to an improvement in pneumatic conveyer switches.

The object of the invention is to produce a 15 switch for pneumatic conveyer systems for directing the discharge into different delivery pipes which shall be simple in construction, efficient in operation, and inexpensive of manufacture. To these ends the 20 present invention consists in the switch hereinafter described and particularly defined in the claims.

In the accompanying drawings illustrating the preferred form of the invention, 25 Fig. 1 is a plan view, Fig. 2 is a side elevation, and Fig. 3 is an end elevation of the switch embodying the present invention; Figs. 4, 5 and 6 illustrate the switch parts in different positions.

30 The illustrated embodiment of the invention is described as follows: The supply pipe 10 is provided on its end with a sliding sleeve 11 having on its under side a shoe 12 which is supported by the track 35 13. To the under side of the shoe 12 is secured a plate 14 to which are attached ropes 15 and 16 extending over pulleys 17 and 18, by means of which the sliding sleeve may be moved to the right or to the left. 40 When moved to the left it slides on to the end of the supply pipe 10; when moved to the right it enters the end of the switch pipe and delivers the material entering the supply pipe thereinto. The sleeve is stiffened by a lip 19 at the end which slides over the supply pipe and is tapered at its other end 20 where it enters the switch pipe.

45 One delivery pipe is indicated at 21, and the other delivery pipe is indicated at 22. 50 These delivery pipes taper to round ends 23 and 24 respectively, which enter round delivery pipes extending therefrom if it is desired to convey the material beyond the switch point. The delivery pipe 21 is provided 55 with a hinged section 25 pivotally mounted on the hinge 26 mounted on the delivery

pipe 21. The receiving end of the delivery pipe 21 is cut on a diagonal, as shown, and reinforced by the rib 27. The delivery pipe 22 is similarly cut on a diagonal in the 60 opposite direction, and similarly ribbed. The end of the switch pipe 25 which enters the delivery pipe 21 is cut on a diagonal 28, so that when it occupies the position shown in Fig. 4, it is received in the 65 end of the delivery pipe 21 with a proper lap. The receiving end 29 of the switch 25 is provided with the reinforcing lip 30. The other switch 31 is provided with a curved receiving end 32 having a reinforcing lip 33. The switch pipe 31 has a diagonal cut end 34, which, when it occupies the position shown in Figs. 1 and 6, extends into the end of the delivery pipe 22 with the proper lap. The 70 switch pipe 31 is hinged to the delivery pipe 22 by the hinge 35, mounted on the receiving end of the delivery pipe 22. The two switches 25 and 31 are connected by a bar 36 to which they are respectively 75 pivoted at 37 and 38. A rope 39 extends from one end of the bar 36 to the pulley 40, and a rope 41 from the other end of the bar 36 extends to the pulley 42, over which it passes. The various pieces of piping and switches are supported by the frame work shown. Thus, two vertical angle bars 43 and 44 support the two cross-bars 45 and 46 between which the delivery pipe 10 is supported. The angle bars 47 80 and 48 extend across the two delivery pipes and are supported by the vertical angle bars 49 and 50. The angle bars 47 and 48 are connected by two pairs of angle bars 85 with the angle bars 45 and 46. Thus, one 90 pair of angle bars 51 extend on one side of the switch, and another pair 52 extend along the opposite side of the switch, and attached to the angle bars 47 and 48 are the vertical supports 49 and 50, or both. A 95 supporting angle bar 53 extends across from between the lower angle bar 51 and the lower angle bar 52, and constitutes a support for the switches 25 and 31.

100 The switch is operated in the following manner. Assuming the supply pipe 10 to be discharging into the delivery pipe 21, as illustrated in Fig. 4, the switch pipe 25 occupies the position shown in such figure, and the sliding sleeve pipe 11 connects the supply pipe directly to the mouth of the switch pipe 25, and it will be seen that the 105 110

material such as wool carried through the pipe by the air passing therethrough is not impeded in its movement, but may pass freely through a continuous unobstructed 5 pipe having no interstices or spaces for catching or holding the material. Now, if it is desired to change the discharge from the pipe 21 to the delivery pipe 22, the operator pulls on the rope 16, thereby sliding 10 the sleeve 11 to the left on to the end of the supply pipe 10, and then pulls upon the rope 39 which causes the switch pipes 25 and 31 to be swung upon their pivots from the position shown in Fig. 4, through 15 the position shown in Fig. 5, to the position shown in Fig. 6. Thereupon the rope 15 will be pulled upon and the sliding sleeve will return to its operative position with its tapered end inserted in the mouth of 20 the non-straight switch pipe 31. Then the discharge of the material being conveyed through the pipe will pass from the supply pipe 10 through the connecting pipe 11 and pass into the switch pipe 31, and thence 25 move into the delivery pipe 22, and in its passage through the pipes there are no obstructions or places where the material may catch or collect.

It is within the purview of the invention 30 to provide a plurality of delivery pipes with a plurality of switch pipes, so that any one of them may be connected with the supply pipe to receive the material being conveyed through the pipes and to discharge it into the desired delivery pipe.

The important feature of the invention resides in the use of a connecting pipe which is moved into inoperative position when it is desired to throw the switch to change 40 the delivery, i. e., it resides in providing pivoted switch pipes and a movable pipe section for connecting the supply pipe to the delivery switches adapted to be moved from operative to inoperative position when 45 the switch pipes are to be moved.

Having thus described the invention, what is claimed is:

1. A pneumatic conveyer switch having, in combination, a supply pipe, a plurality 50 of discharge pipes, a hinged switch pipe for each discharge pipe supported to swing into position in line with the supply pipe, and a sliding sleeve pipe for connecting the supply pipe with the hinged pipe located 55 in operative position.

2. A pneumatic conveyer switch having, in combination, a supply pipe, a plurality of discharge pipes, a hinged switch pipe for each discharge pipe each supported to swing 60 from operative to inoperative position, and a movable connecting pipe adapted to be

moved from operative to inoperative position when it is desired to change the position of the hinged switch pipes, and to be moved from inoperative to operative position after the hinged switch pipes have been moved. 65

3. A pneumatic conveyer switch having, in combination, a supply pipe, a plurality of discharge pipes, a hinged switch pipe 70 for each discharge pipe, a movable pipe section for connecting the mouths of the hinged switch pipes with the discharge end of the supply pipe, means for connecting the switch pipes together so that they may be 75 moved, the one from and the other into operative position.

4. A pneumatic conveyer switch having, in combination, a supply pipe, a plurality of discharge pipes, hinged switch pipes having their discharge ends entering the discharge pipes, a movable connecting pipe for connecting the discharge end of the supply pipe with the receiving mouth of the switch pipe in operative position, and means for 80 moving the switch pipes to move one switch pipe out of operative position at the same time another switch pipe is moved into operative position. 85

5. A pneumatic conveyer switch having, 90 in combination, a supply pipe, a discharge pipe in line therewith, a straight hinged switch pipe pivoted to the discharge pipe and adapted to be moved into and out of line with the supply pipe, a connecting pipe 95 for connecting the supply pipe with the receiving mouth of the switch pipe adapted to be moved from operative to inoperative position to permit the switch pipe to be moved out of and into operative position, a 100 side delivery pipe, a non-straight switch pipe pivotally mounted thereon adapted to be swung with its mouth into position in line with the supply pipe to receive the end 105 of the connecting pipe when in operative 110 position so as to discharge the material received from the supply pipe into the side delivery pipe.

6. A pneumatic conveyer switch having, in combination, a supply pipe, a plurality 110 of discharge pipes, a movable switch pipe for each discharge pipe supported to move from inoperative position out of line with the supply pipe into operative position in line therewith, and a sliding sleeve pipe for 115 connecting the supply pipe with the movable switch pipe located in operative position.

In testimony whereof I have signed my name to this specification.

JOSEPH L. CUSHING.
